UNITED STATES PATENT OFFICE.

REINHOLD SCHMIDT, OF DÜSSELDORF-OBERKASSEL, GERMANY, ASSIGNOR, BY
MESNE ASSIGNMENTS, TO N. V. HOLLANDSCH PATENT EXPLOITATIE MAAT-
SCHAPPIJ, OF ROTTERDAM, NETHERLANDS.

TIME-STAMP.

1,372,911.

Specification of Letters Patent. Patented Mar. 29, 1921.

Application filed March 10, 1920. Serial No. 364,865.

To all whom it may concern:

Be it known that I, REINHOLD SCHMIDT, citizen of the German Republic residing at Düsseldorf-Oberkassel, Germany, have invented certain new and useful Improvements in Time-Stamp, of which the following is a specification.

This invention relates to a time stamp with type wheels which are adjusted with respect to stepped disks by a forward movement of rails having abutments, said stepped wheels being driven by a clock-work. Time stamps of this kind are known; in those contrivances the stamp proper and the clock-work, as well as the stepped disks, are arranged in a common casing so that the handling of such a stamp is rather troublesome. It is also known to introduce the paper to be stamped, *i. e.* a strip of paper, into the stamp and to effect the stamping by depressing a lever, but such devices are restricted to strips, whereas it is often necessary also to stamp larger pieces of paper, such as sheets or the like.

This is made possible by my improvements the essential feature of which is the separation of the time stamp proper from the clock-work with its stepped disks, the arrangement being such that the stamp proper need only be shoved into the clock-work casing in order to be properly adjusted. The time stamp thus constructed is very convenient and handy and may be employed for stamping all kinds of articles in that it is employed like an ordinary hand stamp as generally known.

In order to make my invention more clear, I refer to the accompanying drawing, in which similar letters denote similar parts throughout the several views, and in which:

Figure 1 is a vertical section through a time stamp constructed according to my invention;

Fig. 2 is also a vertical section taken at right angles to that of Fig. 1;

Fig. 3 is a horizontal section on line A—B of Fig. 1;

Fig. 4 is a vertical section through the

stamp part indicated by the line C—D of Fig. 1.

Fig. 5 is also a vertical section through the stamp part indicated by the line E—F of Fig. 1, and

Fig. 6 is an enlarged detail view of certain slides comprised in the mechanism and the parts immediately associated therewith.

The clock-work 1 is arranged in the casing 2 and drives in known manner by means of its minute shaft 3 the shaft 6 by the mediation of a spring 5 attached to a disk 4, and by the mediation of a crank pin 7. The shaft 6 supports three stepped disks, viz. the disk 8 for the unit minutes, the disk 9 for the tens minutes, and the disk 10 for the hours. The stepped disks 8 and 9 are firmly connected with the shaft 6 and rotate with the same speed as the minute hand of a clock, that is to say, they make one complete rotation in one hour. The stepped disk 10, however, sits loosely upon the shaft 6 and is driven by the mediation of the cog-wheel pairs 11 and 12 with a speed corresponding to that of the hour hand of a clock. The disk 8 is provided with six equal lugs, each of which has ten steps. The disk 9 has six steps distributed around its circumference, and the disk 10 has twelve steps also distributed around its circumference. Such stepped wheels are known, as well as their action.

The shaft 6 is supported in the partition walls 13 which hold bolts 17 serving to guide three vertical slides 14, 15, 16 which are displaceable parallel to the disks 8, 9, 10 in a vertical direction. Each slide has a lug 18 which when the respective slide is depressed contacts with the respective stepped disk, that is to say, the lug 18 of the slide 14 contacts with the disk 8; the lug 18 of the slide 15 contacts with the disk 9; and the lug 18 of the slide 16 contacts with the disk 10. The slides 14, 15, 16 have upwardly extending elongated fingers 19, 20, 21 which are different in length corresponding to the greatest possible displacement of said slides. The casing 2 has an upward extension 22

which incloses the upper ends of the slides 14, 15, 16, *i. e.*, the fingers 19, 20, 21.

The time stamp proper, although involved in a certain relative arrangement with respect to the combination and arrangement of parts above described, is in itself a separate combination and arrangement of parts, which is supported by the extension 22 of the casing 2. 23 is the casing of the time stamp proper; it has a handle 24; its lower end extends into the part 22. Said lower end has upon an axle 25 three type wheels 26, 27, 28 which are loosely rotatable upon said axle. 26 is the type wheel for single minutes, 27 is the type wheel for tens of minutes, and 28 is the type wheel for hours. Each type-wheel is connected with a cog-wheel 29 which meshes with a large cog-wheel 30 that is located above it and is firmly connected with a small cog-wheel 32; these two cog-wheels 30 and 32 are loosely rotatable upon a shaft 33. Each of the small cog-wheels 32 meshes with a rack 34 which is attached to a slide 35. There are thus three such slides. Each of them has four slots 36 through which extend four bolts 37 by which the slides are guided, and each has at its lower end a lug 38 which extends into a hole provided in the bottom of the casing 23. These lugs and holes are so arranged that when the time stamp, or its casing 23 respectively, is shoved into the elongation 22 of the clock-work casing 2, each of the fingers 19, 20, 21 enters one of the said holes and contacts with the respective lug 38 of the respective slide 35.

39 are helical springs which constantly tend to pull the slides 35 downward, and 40 are vertical slides which are also guided by the bolts 37 and have each a large cut-out embracing the respective cog-wheel 30. At the lower end of each cut-out is an upwardly extending tooth 41 which takes into the respective cog-wheel 29 when the respective slide moves upward.

The three slides 40 are connected at their upper ends by a cross-piece 65, and by this cross-piece with a bar 42 which extends through the handle 24. 43 is a spring constantly tending to force the bar 42 upward, and 44 is a knob forming the upper end of said bar. The effect of the spring is also to make the teeth 41 engage the cog-wheels 29, if the knob 44 is not depressed.

Between each two slides 40 are two small rolls 45 which are adapted to glide upon oblique surfaces of a horizontal slide 46 which has a pin 47 against which is pulled a bell-crank lever 48 by means of a spring 49. The horizontal arm of the bell-crank lever 48 extends a little out of the casing 23. When introducing the casing 23 into the casing 22, said horizontal lever arm is moved inward by contacting with the curved sur-

face 50 provided at the upper side of the 65 central opening of the lid of the casing 22, and by that movement of the said lever arm, the horizontal slide 46 is laterally displaced by the mediation of the other arm of the said bell-crank lever and the pin 47. Hereby the slides 40 which are connected by the cross-piece 65 are moved downward, so that the teeth 41 leave the cog-wheels 29.

The handle 24 is rotatable upon the casing 23 and has at its inner end a disk 51 to 75 which is attached a downwardly extending rail 52 having at its lower end a bolt 53 which is held in an elastically yielding bearing. 54 is a spring which is affixed at one end to the disk 51 and at the other end to 80 the casing 23 and which tends to turn said disk and the rail 52 in such a direction that one end of the upper slot 55 which is provided in the rail 52 contacts with a stationary horizontal bolt 56 extending through the 85 casing 23, whereas one end of the lower slot 55 also provided in the rail 52 contacts with the shaft 33.

At the inner side of the casing 22 is a vertical slot 57 which has several notches 58; 90 another slot 60, extends parallel to said slot 57; 59 is a connection at the lower ends of said slots.

When the casing 23 is introduced into the casing 22, then the teeth 41 are disengaged 95 from the cog-wheels 29 by means of the lever 48 so that the springs 39 are capable of pulling the slides 35 with the racks 34 into the lowest position whereby the type disks are adjusted to zero. Furthermore, 100 the bolt 53 engages at the same time the first notch 58 so that the time stamp proper cannot be drawn out of the casing 2, but can only be further depressed into its deepest position in which by a slight rotation of 105 the handle 24 the bolt 53 is moved into the vertical slot 60 through the connecting slot 59 after which the stamp is free to be withdrawn from the casing 22.

On introducing the stamp proper into the 110 casing 2, *i. e.*, into its neck 22, and pressing it down into the same, the lugs 38 push upon the fingers 19, 20, 21 and depress the slides 115 14, 15, 16 and put the springs 67 under tension, which latter thus tend to return the 115 slides into their former position. Owing to this downward movement of the slides, the lugs 18 of the same come into engagement with the stepped disks 8, 9, 10 and during the further downward movement of 120 the stamp the now stationary slides 14, 15, 16 or more precisely, their fingers 19, 20, 21 shove the slides 35 of the stamp upward, whereby the type wheels are adjusted according to the position of the stepped disks 125 at the respective moment, that is to say, according to the hour and minute in which that movement takes place.

- When the stamp has arrived in its lowest position, in which it is possible to move the bolt 53 through the connecting slot 59, then the lever 48 gets behind a ledge 61 provided 5 in the neck 22 of the casing 2, in consequence of which the teeth 41 engage the cog-wheels 29 whereby the type wheels are secured in their adjusted position. Thus, when the stamp is drawn out of the neck 22, 10 the type-wheels remain in the position which they have received by the manipulation before described, since the lever 48 may pass over the ledge 61 without the slide 46 being moved. The stamp is now ready for use, 15 i. e., for stamping the time upon the respective article or articles. After this, the button 44 is depressed whereby the teeth 41 are made to leave the cog-wheels so that these are no more checked; the type disks return 20 now automatically to the zero position. If the button 44 should not be depressed, the type wheels would remain in their adjusted position and a wrong time would be stamped when the stamp is used over again.
- 25 In the bottom of the casing 2 is a slot 63, by means of which the clock-work may be adjusted by the action of the cog-wheel 12. Turning the clock-work back is prevented by a pawl 64.
- 30 I claim as my invention:
1. In a time stamp, the combination with a casing, open at one end, a clock-work in the same, vertically movable slides adapted to be operated by said clock-work, and lugs 35 extending from said slides toward the open end of said casing; of a second casing adapted to be inserted into the open end of the first casing; type wheels arranged within the second casing, and means to automatically adjust the said typewheels according to the position of the said lugs.
  2. In a time-stamp, the combination with a casing having an open end; of another casing adapted to be inserted into the open 45 end of the first casing; a clock-work situated within the first casing, and comprising stepped disks and vertically movable slides, the said stepped disks forming abutments for the said slides; lugs extending from the 50 slides; a set of slides adapted to be displaced by said lugs; type-wheels adapted to be adjusted by the second-named slides according to the position of the said stepped disks, the said second-named slides and the 55 said type wheels being located in the second casing; and means to release the type-wheels after an imprint.
  3. In a time-stamp, the combination of a casing having an open end; a set of differently stepped disks in said casing; a clock-work adapted to rotate said stepped disks; slides adapted to be operated by said clock-work in proportion to the passage of time; a second casing adapted to be inserted into

the open end of the first casing; a set of type-wheels in the second casing; a set of slides adapted to be actuated by the first-mentioned slides and to actuate in their turn the said type-wheels; means to retain the said type wheels in position after their adjustment, and means to release said retaining means.

4. In a time-stamp; the combination of a casing having an open end; a set of differently stepped disks in said casing; a clock-work adapted to rotate said disks; slides adapted to be displaced by said clock-work in accordance with the passage of the hours and minutes, said slides comprising lugs of different lengths, a second casing adapted 75 to be inserted into the open end of the first casing; slides adapted to be displaced by said lugs; a set of type-wheels adapted to be adjusted by the second-named slides; retaining means for the adjusted type-wheels; 80 and two releasing means for said retaining means, one of them being adapted to be operated by hand, the other being automatically actuated on introducing the second 85 casing into the first casing.

5. In a time-stamp, the combination with a clock-work casing, of a time stamp casing adapted to be introduced into said clock-work casing; the clock-work comprising stepped disks adapted to be rotated by the 90 clock-work in a manner corresponding to the hands of a clock and a corresponding number of slides adapted to be moved forward in proportion to the rotation of said 95 stepped disks; the time stamp casing containing slides adapted to be displaced by the first-named slides, type disks adapted to be rotated and adjusted according to the displacement of said second-named 100 slides, a yieldingly mounted detent-bolt 105 adapted to engage the time stamp casing immediately after its insertion into the clock work casing, a rotatable handle upon the time stamp casing, and means whereby said handle operates said bolt after the complete 110 insertion of the time stamp casing into the clock work casing so as then to allow of the removal of the said time-stamp casing from said clock work casing, substantially 115 as shown and described.

6. In a time stamp, the combination of a main casing having an open end; a clock work therein; slides arranged in said casing for operation by said clock work and comprising lugs extending toward the open end 120 of the casing; a second casing adapted to be inserted into the open end of the main casing; type-wheels within the second casing; and means for automatically turning said type wheels according to the position 125 of said lugs when the second casing is inserted into the first casing.

7. In a time stamp, the combination of a

main casing having an open end; a clock work in said casing; slides arranged in said casing for operation by said clock work and comprising lugs extending toward the open 5 end of the casing; a second casing adapted to be inserted into and withdrawn from the open end of the first casing; type wheels arranged within the second casing; means for automatically turning the type wheels 10 according to the position of said lugs when

the second casing is introduced into the first casing; means for automatically locking the type wheels in adjusted position to enable an imprint after said second casing has been withdrawn from said first casing; and means 15 for releasing said locking means after the imprint has been taken.

In testimony whereof I affix my signature.

REINHOLD SCHMIDT.
